Primary Examiner — Cynthia M Chin*(74) Attorney, Agent, or Firm* — Fox Rothschild LLP**CLAIM**

The ornamental design for a toy rollercoaster track section, as shown and described.

DESCRIPTION

FIG. 1 depicts a top perspective view of a toy rollercoaster track section.

FIG. 2 depicts a bottom perspective view of the toy rollercoaster track section of FIG. 1.

FIG. 3 depicts a front elevation view of the toy rollercoaster track section of FIG. 1.

FIG. 4 depicts a rear elevation view of the toy rollercoaster track section of FIG. 1.

FIG. 5 depicts a right elevation view of the toy rollercoaster track section of FIG. 1.

FIG. 6 depicts a left elevation view of the toy rollercoaster track section of FIG. 1.

FIG. 7 depicts a top plan view of the toy rollercoaster track section of FIG. 1; and,

FIG. 8 depicts a bottom plan view of the toy rollercoaster track section of FIG. 1.

The broken lines in the drawings illustrate environmental structure on the article and form no part of the claimed design.
